TUMBLER WASHING DEVICE

Vincent W. Cunningham, Chicago, Ill., assignor
to John Cunningham, Riverside, Ill.

Application October 5, 1929, Serial No. 397,486
Renewed January 14, 1936

8 Claims. (Cl. 15—75)

The invention relates to washing devices and more particularly to improvements in tumbler washing devices employing a scrubbing action to clean the glass.

5 Tumbler washing machines are, in general, of the brushing or physical scrubbing type, or of the chemical reagent type in which a suitable solution is used to dissolve the foreign matter to be removed.

10 Devices of the first type have not thus far been extensively adopted because prior designs have been attended in use with excessive breakage of glassware, and have not been such as to permit the cleaning of tumblers of various sizes and contours in a single machine. Scrubbing machines have furthermore been incapable of performing the brushing action in the presence of an adequate supply of liquid solvent with the result that the potential effect of the scrubbing action has not been fully realized, nor has the necessary degree of cleanliness been attained.

15 Devices of the chemical reagent type are incapable of completely removing surface film and foreign matter except by the use of reagents which are, in themselves, poisonous in nature and too expensive to be practicable commercially. Practical safety considerations have accordingly restricted such devices to the employment of mild commercial alkaline soaps which are not sufficiently active of themselves to penetrate and dissolve the foreign material and grease film which clings to the surface of used glassware. This inherent limitation of machines of the latter type renders them incapable of completely removing surface film and results in imperfect cleansing with the result that the liquid solvent, in draining from the surface of a tumbler is inclined to rupture and flow in small rivulets rather than in a continuous and unbroken stream as is the case when the surface is perfectly clean. The surface of the glassware is left in a streaked condition as a result of this action, and the remaining film is augmented by the dirt suspended in the solution with which it contacts.

20 It has accordingly been impossible to effect a thoroughly sanitary condition of used glassware, it being necessary to finally submit tumblers to a hand polishing operation, the effect of which is to uniformly distribute rather than remove the film remaining upon their surfaces after the washing operation. Hand polishing has been an expensive and unsanitary expedient resorted to for the purpose of partially correct-

ing the imperfect cleansing action of the washing devices.

It is therefore a general object of the present invention to produce a new and improved tumbler washing device of the scrubbing type which overcomes the foregoing difficulties. In carrying out this object, I have provided a scrubbing device of novel construction in which the internal and external surfaces of tumblers of various sizes and contours may be simultaneously subjected 10 to a scrubbing action in the presence of a liquid solvent.

Still another object is to provide a novel tumbler scrubbing device having internal and external scrubbing elements in which one element 15 is flexibly mounted with respect to the other element so as to eliminate vibration and the breakage of fragile glassware.

20 A further object of the invention is to provide a new and improved tumbler scrubbing device having internal and external scrubbing elements of which the external elements are removably mounted on the inner surface of a rotatable cylindrical housing open at one end, and the internal element is threaded upon a stub 25 shaft coincident with the longitudinal axis of the housing, so that the external elements may be removed from the open end of the container and the internal element thereafter unscrewed from the stub shaft for inspection or replace- 30 ment of the brush elements.

25 A further object is to provide a tumbler scrubbing device in which a brushing element is mounted on the inner surface of a rotatable cylindrical housing closed at one end and open at the 35 other end and in which the open end is partially closed by an annular removable guard of resilient material whose inner edge is adapted to provide a yieldable guard for a tumbler in the process of being washed and to retain within the cylindrical housing a supply of liquid solvent adequate to 40 maintain the brushing element in a wetted condition.

30 Ancillary objects and advantages will become 45 apparent from the following description taken in connection with the accompanying drawings in which:

Figure 1 is a perspective view of the scrubbing device constituting the preferred embodiment of 50 the invention.

Fig. 2 is a horizontal sectional view of the device taken along line 2—2 of Fig. 1.

Fig. 3 is an enlarged vertical sectional view taken along the line 3—3 of Fig. 2.

Fig. 4 is an enlarged sectional view taken along the line 4-4 of Fig. 3.

Fig. 5 is a perspective view of the internal brush element.

5 For purposes of description, I have illustrated in the drawings and will hereinafter describe in detail the preferred embodiment of the invention with the understanding that I do not intend to limit the invention to the particular construction 10 and arrangement shown, it being contemplated that various changes may be made by those skilled in the art without departing from the spirit and scope of the appended claims.

15 Referring more particularly to the drawings, the invention in its preferred form is embodied in a scrubbing device having a housing 10 which provides, in the present instance, a portable container for a complete scrubbing unit assembly. The housing 10 may be made of any suitable material, 20 preferably metal, and may have any desired form. In the present instance, the housing 10 comprises side walls 11 and 12 and end walls 13 and 14 respectively which rise from a rectangular base 15 and are surmounted by a cover 25 16 removably secured to the end walls by set screws 17. Preferably, the end walls 13 and 14 extend above the side walls 11 and 12, and are rounded at the top. The cover 16 is curved laterally to conform to the end walls, and thus lends 30 itself to economy in space and external attractiveness. The under side of the base 15 is provided with suitable cushions 18 to permit the device to be operated upon enameled or finished surfaces without injury thereto. Formed in the 35 end wall 13 is a circular opening 19. An aperture 20 of any desired contour is also formed in the wall 13 and opens down to the upper surface of the base 15.

40 Rotatably journaled within the housing 10, with its longitudinal axis substantially coincident with the center of the circular opening 19, is a cylindrical container 21. In the present instance, the container 21 is provided with a closed inner end 22 and an open end 23 which is adapted 45 to rotate in a plane parallel to, and inwardly of the wall 13. In the embodiment of the invention herein selected for purposes of disclosure the cylindrical member 21 is driven by a rearwardly extending shaft 24 secured to, and coaxial with, 50 the closed end 22. The shaft 24 is rotatably supported in a bearing 25 which in the present instance is formed integrally with a transversely extending partition wall 26. The latter serves to 55 divide the interior of the casing into substantially non-communicating compartments 27 and 28.

55 A suitable driving mechanism for the shaft 24 is mounted in the compartment 28. In the present instance, this mechanism comprises an electric motor 29 operatively connected to the rearwardly extending end of the shaft 24 by means of a reduction gearing generally indicated at 30. To insure correct alignment and coaction between the driving and driven elements of the unit, the driving motor together with the container 21 60 and the intermediate reduction gearing 30 are mounted on a common supporting member. To this end, the motor 29 is supported on a bracket 31 rigidly secured to the partition wall 26 as by means of bolts 32.

70 Provision is made to induce a circulation of air through compartment 28 to prevent overheating of the driving motor which, in the present instance, comprises a fan 29a rigid with a protruding end of the motor shaft and adapted to circ-

ulate air through louvers 11a and 12a formed in the side walls 11 and 12 respectively.

For the purpose of compensating for end thrust occasioned by alternately applying and withdrawing a tumbler to and from the scrubbing member, and for the further purpose of eliminating noise and vibration, the wall 26 is mounted in cushioned relation to the housing 10. In effecting this purpose, the wall 26 is formed at its lower margin with a pair of forwardly extending lugs 10 33 secured to the base 15 by means of screws 34, and a pad 35 of resilient material, such as rubber, is interposed underneath each lug to provide a flexible mounting. Thus, the upper part of the wall 26 is free to yield forwardly or rearwardly 15 as force is applied axially of the member 21 incident to moving a glass into and out of scrubbing position, the resiliency of the wall as well as its mounting on the base 15 contributing to that effect. To limit rearward movement of the wall, 20 a pair of lugs 36 are formed integrally with the respective side walls 11 and 12, and project inwardly to the rear of the wall. The opposed edges of the wall are shielded from direct contact with either of the side walls or the lugs 36 by 25 means of suitably formed resilient cushions 37.

30 Referring to Figs. 3 and 4, the container 21 is provided with a pair of opposed longitudinal inwardly facing brushes 39. In the present instance, these brushes are removably secured to the inner peripheral wall of the container by flanged retaining guides 40. A brush 41 substantially coextensive with the brushes 39 is removably mounted within the container and in coaxial relation thereto, and the rearward end 35 of its core is removably connected to the forward end of the shaft 24 as by means of a screw thread 42.

40 By reason of the relatively fixed relation of the container 21 and the shaft 24 the external brushes 39 and the central or internal brush 41 are adapted to rotate in unison thereby preventing a frictional engagement between the brushes with an accompanying waste of power and excessive wear 45 of brush elements.

45 Provision is made for the simultaneous scrubbing of the interiors and exteriors of tumblers of widely varying dimensions and contours without affecting the relatively fixed positions of the brush elements. In furtherance of this end, the bristles of the central or inner brush are partially cut away at two diametrically opposed points to provide recesses opposite each of the external or peripheral brushes, thereby permitting the employment of peripheral brushes whose bristles overlap the arc defined by the remaining bristles of the central brush. It will be apparent from Fig. 4 that this construction enables the device to operate effectively on tumblers varying 50 in diameter from a minimum defined by the distance between the inner ends of the peripheral or external brushes, to a maximum determined by the maximum diameter of the internal brush.

55 Suitable means is provided to effect registration 60 of the peripheral brushes with the recesses in the central brush. In this instance, this means comprises a central flanged sleeve 38 rigidly secured to the end wall 22 of the container 21 by any desirable means such as bolts 44. The sleeve 70 38 is slidably adjustable upon the stub shaft 24, and non-rotatably secured relative thereto by means of a set screw 45.

65 An outwardly protruding brushing element 43 is secured to the outer end of the central brush 75

41 to insure an intimate and thorough scrubbing action upon the inner bottom surface of the tumbler.

It is contemplated that the placing of fragile 5 glassware on the central scrubbing element eccentrically of the axis thereof will create unbalanced forces which will give rise to vibration within the machine and may possibly cause the breaking of the tumbler. To this end the central 10 brush is yieldably mounted upon the stub shaft 24 by means of a flexible cylindrical coupling 46 which is secured to a shouldered head 47 upon the screw 42 by means of a bolt 48.

The effectiveness of the scrubbing operation 15 is dependent upon the presence of a suitable liquid solvent which is maintained in a turbulent or moving condition relative to the brushing elements so as to effect a constant flushing action. In the present embodiment of the invention this 20 purpose is accomplished by providing the open end of the container 21 with an inwardly extending peripheral flange 49 of such width as to retain within the container an appreciable quantity of solvent when the device is stationary. 25 In operation the inertia of the liquid solvent prevents it from immediately partaking of the movement of the container with the result that it moves relative to the brushes so as to effect a washing action upon the brushes themselves.

30 The motor means is of such strength that the insertion of a tumbler in the scrubber effects an appreciable retardation of the speed of rotation of the container with the result that the liquid solvent contained therein will again move relative to the brushes due to the effect of the kinetic energy acquired from the moving container and the liquid will again effect a cleansing action upon the brushes. During operation, the container will retain a large quantity of liquid 35 in excess of that which can be held when at rest with the result that the stopping of the machine permits the excess solvent to fall about the peripheral and central brushes and flow from the machine carrying with it the entrained foreign matter.

40 Preferably, the peripheral flange 49 is of a resilient material such as rubber so as to provide a cushioning effect for both the tumbler being operated upon and the fingers of the operative while holding a glass in the scrubbing position. The flange 49 is made removable to permit the replacement of either of the peripheral brushes and the subsequent removal of the central brushing element for replacement or 45 repair. In the present instance, flange 49 engages a peripheral bead 50 formed on the open end of the container. To further protect the operative as well as the glassware being operated upon the circular opening 19 is provided 50 with a resilient flange 51.

55 In operation, the container 21 is brought to its normal operating speed by the motor means after which a quantity of solvent is poured into its open end. When the brushes have become thoroughly wetted with the solvent the operative grasps the tumbler to be washed near its bottom edge and thrusts the open end of the glass into the container. The central brush effects a scrubbing of the interior of the glass simultaneously with the action of the peripheral brushes in scrubbing its exterior. Immediately after removal the tumblers are subjected to a rinsing operation and then permitted to drain. The surface tension of clean water is greater than 60 the adhesive effect between the water and the

surface of the glass with the result that the film of water remaining upon the glass after the rinsing operation will completely drain from its surface without breaking thereby leaving the glass free of water spots and in a dry and clean 5 condition.

65 By reason of the rearward position of the open end of the container with respect to the circular opening 19, solvent which may be thrown therefrom during its rotation will impinge against the inner top and side walls of the housing and will be drained from the compartment 27 through the aperture 20.

70 The partition wall 26 in addition to serving as a common supporting member for the mechanism, functions to prevent the flowing or splashing of the liquid solvent upon the motor means.

75 Thus it will be seen that a completely self-contained portable tumbler scrubbing device has been provided which is capable of physically 20 scrubbing a tumbler in the presence of an adequate supply of solvent thereby effecting a complete removal of foreign material from its surfaces.

I claim as my invention:

25 1. A tumbler scrubber comprising a rotatable cylindrical container, a plurality of brush elements mounted inwardly of said container and adapted to have a tumbler projected into scrubbing relation therewith, motor means to rotate 30 said container and a common supporting member for said container and motor means, said member being resiliently supported whereby it is adapted to yieldably resist the thrusting of a tumbler into operative relation with said brush. 35

2. A portable tumbler scrubber comprising, in combination, a base, a wall member yieldably mounted on said base, a cylindrical container adapted to retain liquid and rotatably journaled in said wall, a plurality of brushing elements 40 interiorly of said container and non-rotatable with respect thereto, said brushing elements being adapted to have a tumbler thrust into engagement therewith, and motor means rigidly mounted on said wall in operative relation with said 45 container, said motor means and said container yielding in unison with said wall under the influence of a thrust exerted in applying a tumbler to or removing it from said brushing elements.

3. A scrubber of the character described comprising a cylindrical member adapted to rotate about its longitudinal axis and having an inwardly extending peripheral flange on one end and a driving shaft on the opposed end, a single segmental brush element flexibly secured to the inner 55 end of, and coaxial with said driving shaft, a plurality of independent inwardly extending brush elements removably secured to the inner surface of said cylindrical member, the bristles of said inwardly extending brushes extending inwardly of the circumference defined by the ends of the segments of said central brush, and means adjustably connecting said member and said driving shaft to permit relative adjustment therebetween so as to position said inwardly extending brush elements between the segments of said central brush. 60

4. A tumbler scrubber of the class described comprising, in combination, a driving shaft, a substantially cylindrical brush having radially extending bristles, a portion of said bristles being cut away to define a groove, said brush being threaded axially into said shaft to rotate therewith, a cylindrical container substantially co-extensive with and enveloping said brush, a second 70

75

brush removably mounted on the inner peripheral surface of said container, the bristles of said second brush being adapted to extend radially inwardly of the groove provided in the bristles of said first mentioned brush, and means adjustably connecting said shaft and said container providing a driving engagement therebetween to effect simultaneous rotation of said brushes and whereby said container may be adjusted by rotation relative to said first mentioned brush to effect a registration between the bristles of said second mentioned brush and the grooves of said first mentioned brush.

5. A scrubber of the character described comprising, in combination, a shaft, a cylindrical brush detachably connected to said shaft for rotation about its longitudinal axis and having radially extending bristles, said bristles being partially cut away to define a groove longitudinally 10 of said brush, a sleeve adjustably mounted on said shaft, a cylindrical container rigid with said sleeve, said container being substantially coextensive with said cylindrical brush, a flanged guide extending longitudinally of the inner surface 15 of said container, a second brush substantially coextensive with said first mentioned brush, said second brush being slidably mounted in said guide, the bristles of said second mentioned brush extending radially inwardly of the circumference defined by the bristles of said first brush, the adjustable mounting of said sleeve on said shaft permitting relative rotative movement between said respective brushes to position the bristles of said second mentioned brush in the 20 groove provided in the bristles of said first mentioned brush whereby said second mentioned brush may be freely inserted and withdrawn from said guide.

6. A portable tumbler scrubber comprising, in 25 combination, a housing having a base and side, end and top walls; one of said end walls having a circular opening therein, a partition member resiliently supported by the base of said housing intermediate said end walls, a cylindrical container 30 rotatably journaled in said partition member with

its axis extending substantially normally of the plane of said member and held against axial movement relative to said member whereby the resilient support of said member is adapted to yieldably resist thrust on said container, said container having an open end spaced inwardly from the opening in said end wall, a brush element mounted in said container for rotation therewith, and motor means drivingly connected to said container.

5

10

7. In a tumbler scrubber, the combination of a rotatable supporting means, a substantially cylindrical brush carried by said means for scrubbing the interiors of the tumblers, a portion of the bristles of said brush being shorter than the other 15 bristles to form a pair of segmental grooves in the brush, said means being rotatable about an axis extending longitudinally through said brush, and a pair of brushes carried by said means for scrubbing the exteriors of the tumblers and extending longitudinally of and into said grooves, the inner end of said exterior brushes extending substantially to the bottoms of said grooves said interior and exterior brushes being relatively adjustable circumferentially to position said pair 20 of brushes in said grooves.

25

8. In a tumbler scrubber, the combination of a rotatable substantially cylindrical container, a brush carried by said container extending longitudinally thereof for scrubbing the interiors of 30 the tumblers and having bristles extending radially outward, a portion of said bristles being shorter than the other bristles, the container being rotatable about an axis extending longitudinally thereof through said brush, and a brush carried by said container for scrubbing the exteriors of the tumblers and having bristles extending radially inward substantially to the outer ends of said shorter bristles, one of said brushes 35 being circumferentially adjustable relative to the other to position the exterior brush and the shorter bristles of the interior brush opposite each other.

35

VINCENT W. CUNNINGHAM.
